BLADE TRACKING MECHANISM FOR
LIFTING ROTORS

Harold T. Avery, Oakland, Calif.

Application March 10, 1947, Serial No. 733,673

15 Claims. (Cl. 170—160.13)

1

The present invention relates to sustaining rotors for aircraft, and particularly to rotors of the articulated type, that is to rotors comprising blades each attached to a central hub by one or more hinges including a flapping hinge permitting of vertical angular displacement of the blade relative to the hub.

In such a rotor each blade is, at each instant, angularly positioned about its flapping hinge in accordance with the resultant of all forces acting on the blade at the instant, including the effect of the momentum and inertia of the blade itself. It is the usual practice in such rotors, particularly in helicopters, to provide some means for effecting cyclic control of pitch so that the blades may be caused to follow some non-symmetrical path or to offset the non-symmetrical effect on the blades of forward flight or other translational movements of the craft.

Unless each blade is an exact duplicate of each other blade both mechanically and in aerodynamic shape it will tend to seek a different angular position and to track higher or lower under at least some conditions of flight. For instance, if one blade has a slight twist tending to give it a slightly higher pitch setting near the tip than that of the other blades it will tend to track higher than the other blades. It is customary to provide some means whereby the pitch setting may be decreased on a blade which is thus found to be tracking too high, but since such means normally serves to reduce pitch over the entire blade the best that it can do is to permit of setting the blade so that the pitch over the inner portion of the blade (that is the portion closer to the hub) will be enough less than that of the other blades to counterbalance under certain operating conditions the remaining excess of pitch setting in the outer portion of the blade. In this manner the blade may be made to track properly on the test stand where the adjustments are made, but under certain flight conditions wherein the proportion of the blade lift contributed by the outer portion of the blade differs considerably from that pertaining under the test conditions the blade will again fail to track properly with the other blades.

The immense variety in the nature and location of the difference in aerodynamic shape that may occur between blades, together with the extreme difficulty and costliness of efforts to entirely eliminate such differences, make it essential that some means be provided for re-tracking blades in order to avoid the eccentric mechanical and aerodynamic forces set up by discrepancies

2

in blade tracking. Present methods of retracking blades are however very slow, awkward and expensive, and though they are capable of providing good tracking under certain chosen sets of operating conditions, they will not in general, prevent the blades from going out of proper tracking and causing vibration under other sets of operating conditions.

It is an object of this invention to cause the 10 various blades of a rotor to automatically seek the same path or track in spite of differences in construction and/or aerodynamic shape of the respective blades.

It is a further object to provide such automatic tracking continuously during flight and in spite of changes in the operating conditions.

It is a further object to equalize the average effective flapping positions of all blades at each point in the circuit, taking into account displacement due to flexing of the blades as well as those due to angular displacement of the blades on their flapping hinges.

It is an object to provide such retracking in a manner that will not affect the average collective pitch of all blades.

It is a further object to control the rate of retracking so that on the one hand it will be sufficiently great so that tracking errors will be minimized substantially as rapidly as they will occur, and yet on the other hand retracking will not occur so rapidly as to produce adverse effects upon the cyclic control of the rotor.

It is also an object to vary the rate of retracking in accordance with the amount of the 35 difference in blade positions, so that large tracking errors can be corrected at rates which, if brought into play by slight cyclic control displacements of the blades, would unduly disturb such slight control displacements.

It is a further object to restrict such variation in the rate of retracking to substantially the maximum range of differences in blade positions that may be related to tracking errors, so that the rate of retracking will increase with increase 45 in size of the tracking error up to the maximum tracking errors that may be anticipated, but will not continue to increase throughout all of the much greater range of differences in blade positions which occur on account of cyclic control

50 displacements within which greater range further increase in the rate of retracking would serve no useful purpose but would unnecessarily increase the adverse effects on cyclic control.

The manner in which the foregoing, together with additional objects and advantages of the

invention, are attained will be made apparent in the course of the following description of the preferred embodiments thereof which is to be read with reference to the accompanying drawings, in which:

Figure 1 is a vertical section of a rotor embodying the invention taken substantially on line 1—1 of Figure 2.

Figure 2 is a plan view of the same rotor, showing schematically the novel valve mechanism for controlling the tracking mechanism.

Rotor construction and drive

The invention is illustrated in Figures 1 and 2 as applied to a three-bladed rotor constructed for the most part, substantially as disclosed in my co-pending United States Patent Application, Serial Number 665,653, filed April 29, 1946, now Patent No. 2,539,562, dated January 30, 1951.

As particularly shown in Figure 1 each blade 10 (the three such blades being identified in Figure 2 as 10a, 10b, and 10c respectively) comprises a skin or covering 11 integrally mounted on ribs 12 which in turn are integrally attached to the tubular blade spar 13, which spar terminates inwardly in a bearing retainer 14 containing a ball thrust bearing 15 co-axial with the adjacent portion of the spar. This bearing serves to attach the blade to the connecting link 16 in a manner permitting of the blade being rotated about the spar axis relative to the link 16, to effect changes in the pitch setting of the blade. Connecting link 16 is in turn attached by means of flapping hinge 17 to lugs 18 integral with hub member 19. Hub member 19 is in turn pivotally mounted by means of roller bearings 20 and 21, for rotation about cylindrical member 22 and about the co-axial cylindrical member 23 which is attached to member 22 by means of a plurality of bolts 24, which bolts together with their co-operating nuts 30 serve to attach both members 22 and 23 to the cylindrical member 31 which is integrally attached to ring 32 and fuselage frame members 33.

Attached to the bottom of hub member 19 by means of a plurality of bolts 34 is a ring 35 having downwardly extending lugs 36 for receiving the roller bearing 20. The spherical roller thrust bearing 37 is interposed between ring 35 and cylindrical member 23, thus serving to transmit to the framework of the craft the upward thrust of hub member 19, which is primarily the force which sustains the craft in flight. Attached to the top of hub member 19 by means of a plurality of bolts 38 (Fig. 2) is a plate 39. Interposed between this plate and a flange 40 (Fig. 1) of cylindrical frame member 23 is ball thrust bearing 41, which serves to sustain the rotor when it is not exerting an upward lift on the craft.

The drive for the rotor comes from the engine, not shown, through transmission shaft 42, which shaft is guided in the upper surface 44 of the cylindrical frame member 22. Integral with the upper end of shaft 42 is gear 50 which meshes with idler 51, which idler is rotatably mounted on stud 52 which is integrally mounted in member 22. Idler 51 in turn meshes with teeth 53 cut into the inner face of hub member 19. Hub member 19 is thus rotated upon the fixed cylindrical member 22, 23 by the rotation of shaft 42 by the engine.

Collective and cyclic pitch setting

As previously described, blade 10 is attached to connecting link 16 in a manner permitting of

the blade being rotated about the blade axis relative to link 16, to effect changes in the pitch setting of the blade. Blade 10 is rotatably positioned about this blade axis by the vertical positioning of the blade pitch controlling means which comprises link 61 connected by a ball and socket joint to arm 60 (Fig. 2) integral with the blade. The length of link 61 is rendered adjustable by constructing it of two sections screwed together and locked by nut 62 (Fig. 1).

The vertical positioning of pitch control link 61 is effected by a pitch control spider 65 comprising arms 64 integral with ring 65a, each link 61 being connected by means of a ball and socket joint to a bell-crank 63 pivotally mounted on a corresponding one of these arms 64. Each pitch control bell-crank 63 is maintained in a fixed position relative to its respective arm 64 except to the extent that it may be displaced relative thereto by the automatic blade tracking mechanism, which is described hereinafter. Pitch control spider 65 is rotated about pitch control ring 66 on ball bearings 67 in unison with the rotor, the force for rotation being supplied by pin 68 which is integrally mounted on hub member 19, and protrudes through a slot in arm 69 integral with pitch control spider 65.

Pitch control ring 66 is integrally attached to pitch control hub 70 by means of arms 71 which arms include necked down round portions 72 which pass through cylindrical member 31 in slots 73. Pitch control hub 70 is attached to collective pitch control rod 74 by ball and socket joint 75. One cyclic pitch control assembly is illustrated in Figure 1, comprising cyclic pitch control arm 80 integrally attached to pitch control ring 66 and attached to cyclic pitch control rod 81 by ball and socket joint 82. There is also another cyclic pitch control assembly (not shown) which comprises another cyclic pitch control arm 80 and rod 81 like those just described, but this assembly is attached to ring 66 at a location displaced ninety degrees from that of the assembly illustrated. The collective pitch control rod 74 and the cyclic pitch control rods 81 are connected by a linkage such that vertical movement of the collective pitch control rod 74 will be accompanied by the same amount of vertical movement of both of the cyclic pitch control rods 81, but the cyclic pitch control rods 81 are each capable of independent vertical movement relative to collective pitch control rod 74. Such a type of linkage is shown on pages 122-130 of the June 1945 issue of "Aviation" magazine, and a different form of such a linkage is shown in my co-pending United States Patent Application, Serial 630,745, filed November 26, 1945, which issued as Patent No. 2,546,881 on March 27, 1951.

The operation of the pitch control assembly is as follows: The upward movement of collective pitch control rod 74 (automatically accompanied by similar upward movement of both rods 81) raises ring 66 without altering its angle of tilt, thereby simultaneously increasing the pitch on all of the rotor blades 10 by means of the linkages previously described. The upward or downward movement of one of the two cyclic pitch control rods 81 relative to collective pitch control rod 74 inclines ring 66 and hence pitch control spider 65 relative to the rotor hub axis at an angle dependent upon the position of the cyclic pitch control rod 81 relative to rod 74. The inclination of pitch control spider 65 causes the rotor blades to increase and decrease their pitch

cyclically; i. e., the pitch is increased by that segment of the pitch control spider that is raised and conversely the pitch is decreased by that segment of the pitch control spider that is lowered on account of the inclination of the pitch control spider. Thus spider 65 and the mechanism which controls it, as above described constitutes the primary pitch adjusting means for the rotor, but its action is subject to alteration by the secondary pitch adjusting means hereinafter described.

Mechanism responsive to blade flexure

Because of the fact that rotor blades are ordinarily constructed of relatively slight vertical dimension and sustain relatively great aerodynamic loads of uneven and cyclically changing distribution along the length of the blade, such blades are ordinarily subjected to considerable flexing in flight, particularly in a vertical direction. If a blade which is attached to the rotor hub by a flapping hinge is appreciably flexed, the effective flapping position of the blade, and therefore its tracking of the other blades, is dependent upon the direction and amount of the flexing of the blade as well as upon the vertical angular displacement of the root section of the blade about the flapping hinge. In order to take both of these factors into account I provide mechanism which is quantitatively responsive to blade flexure as well as to displacement of the blade about the flapping hinge. This mechanism includes a lever 97 (Fig. 1) which is angularly positioned about flapping hinge 17 in response to both vertical flexing of the blade and angular displacement of the blade on flapping hinge 17. This angular positioning of lever 97 is effected by the following mechanism:

Lugs 90 are integrally attached to tubular blade spar 13. Flexible cables or wires 91 are attached to these lugs by means of pins 92 and are led along paths vertically displaced from the neutral axis of the blade through guides 93, each of which guides may consist of a pair of rollers mounted on a lug integral with spar 13. Near the root of the blade each cable 91 is attached to a connecting link 94 by means of a connecting pin 95. Connecting links 94 are pivotally attached by means of pins 96 to lever 97. Pins 96 are placed considerably further apart than are the pins 92 at the outer ends of cables 91, so that the angular displacement of lever 97 will be correspondingly less than that of lugs 90. The reason for this is so that lever 97 will be angularly displaced in proportion to the average effective angular displacement of the blade relative to the hub due to blade flexing, as measured at the flapping hinge. This angular displacement is substantially that of a line connecting the flapping hinge to a point on the blade somewhere in the vicinity of the average effective center of lift of the blade, and is in any case very considerably less in amount than the angle through which the outer tip portion of the blade has been flexed. Therefore, if lugs 90 are located rather close to the blade tip, pins 96 should be about three times as far apart as pins 92 so that lever 97 will be rocked through about one-third the angle through which lugs 90 are deflected, while if lugs 90 are located further in on the blade the ratio of the distance between pins 96 to that between pins 92 should be correspondingly decreased, so that in any case, whether the spacing is determined by theory or by test, the flexing of the blade in flight shall displace lever 97 through an angle equal to that

through which the unflexed blade would have to be rocked around flapping hinge 17 in order to produce substantially the same amount of change of blade tracking effect on the craft.

These same connections to lever 97 will also cause that lever to rock about flapping hinge 17 in unison with the blade, for any given condition of blade flexure. Hence lever 97 is angularly positioned about hinge 17 in accordance with the average effective blade position taking into account both blade flexure and rocking of the blade upon the flapping hinge.

Blade tracking mechanism

As previously indicated it is highly desirable to eliminate all differences in blade tracking under all conditions of operation and mechanism is therefore provided which is sensitive to any differences that may exist between the angular position of the various levers 97 associated with the respective blades, and which is automatically operable to decrease such differences by adjustment of the pitch of one or the other or of both of the blades with reference to which the difference exists. In the preferred form of blade tracking mechanism herein described pitch is automatically adjusted on both of the blades concerned.

This blade tracking mechanism consists of two major parts: the first part constitutes a tracking control means comprising a valve system together with the linkages which supply that system with indications of the differences in blade tracking, and the second part constitutes an operating means comprising a hydraulic system that alters blade pitch in accordance with the responses of the valve system, in a manner adapted to eliminate the differences in blade tracking.

The valve system and its linkages are as follows: In conjunction with each blade there is provided a slide 100 which moves in a guide 101 and is connected to the corresponding lever 97 (previously described) by a slide extension 102, connecting link 103, and pins 104 and 105. Vertical pin 106 is integrally attached to slide 100, and fits in the fork of one arm of a bell-crank 107 (see also Fig. 2) which is pivotally mounted on pin 108 which in turn is integrally mounted in hub member 19. The other arm of the bell-crank is pivotally attached by means of a pin 110 to a link 109, which link is made adjustable in length by constructing it of two pieces clamped together by means of bolts 112 extending through slots 111. Each link 109, in addition to being connected at one end to a bell-crank 107, as previously described, is pivotally connected at the other end to one end of a lever 113 by means of a pin 114. At its opposite end lever 113 is provided with a fork which spans the one of the previously mentioned vertical pins 106 which is positioned by the next adjacent blade. Near its mid-point lever 113 is pivotally attached to a valve-positioning link 115 by means of a pin 116. Link 115 thus constitutes an element jointly positioned by two of the blades in accordance with the difference of the effective flapping angle of the two blades. Each link 115 is normally held in fixed relation to a corresponding slide valve member 117 by means which nevertheless permit of its being yieldably displaced relative thereto in either direction. This means comprises a spring 118 which slips over tenons 119, which are identically shaped on both link 115 and member 117, as parts of identical H-shaped openings in the two members. Each member 115 lies directly

on top of the corresponding member 117 and in the plan view, as illustrated in Figure 2, the portions of these two members extending outwardly from pin 116 are identical. This construction is generally similar to that of the spring link illustrated in Figure 50 of Avery Patent No. 2,271,240 dated January 12, 1942. However, each member 115 terminates inwardly with an arcuate surface concentric with the corresponding pin 116, as shown in dotted lines in Figure 2, while the corresponding slide valve member 117 extends outwardly and includes as an integral part thereof a slide valve 120, the three such valves shown in Figure 2 being identified as 120a, 120b, and 120c respectively. Each slide valve 120 slides in valve sleeve 121 (the respective sleeves being identified as 121a, 121b, and 121c) and its movement therein is limited by stop lugs 122 integral with valve 120. The purposes of the valve override spring 118 is to permit movement of valve-positioning link 115, in either direction after slide valve 120 and the integral extension 117 thereof may have reached the limit of their travel and are prevented from moving by stop lugs 122.

It is to be understood that, as illustrated in Figure 2, the above described valve mechanism is repeated three times for a three-bladed rotor, and that each valve is associated with two adjacent blades. In a manner hereinafter set forth the valve mechanism just described operates to displace one of the three slide valves 120 from neutral whenever there is a difference in effective flapping angle between the two blades with which said slide valve is associated.

Each slide valve 120 thus constitutes an adjustable element positioned by the blades for controlling the blade tracking operation, and, in the manner hereinafter described, these valves act as the controlling members for the pitch adjusting or altering portion of the blade tracking means.

As previously mentioned the second part of the blade tracking mechanism consists of the hydraulic system which constitutes the operating means for altering blade pitch to reposition the blades so as to maintain proper tracking. Hydraulic pressure and hydraulic flow for all three blades is supplied by the single hydraulic pump 130 which is attached to plate 39 by means of a plurality of bolts 131, and plate 39, as previously described, is attached to hub member 19 by means of a plurality of bolts 38. Hydraulic pump 130 is equipped with a conventional spring loaded bypass 132 which is used to permit all excess hydraulic fluid pumped to flow back to intake while maintaining constant hydraulic pressure on the output side of the pump. Hydraulic pump 130 is operated by shaft 133 (Fig. 1) which is turned by spur gear 134 which is integrally attached to shaft 133. Spur gear 134 is rotated by idler gear 135 which turns on stud 136 which is integrally attached to plate 39. Idler gear 135 is, in turn, rotated by idler gear 137 which is free to rotate on stud 138 which is integrally attached to plate 39. Idler gear 137 is rotated whenever the rotor is turning by virtue of the fact that it meshes with gear teeth 139 cut on the inside face of flange 40 of cylindrical frame member 23.

The output side 140 (Fig. 2) of hydraulic pump 130 is connected to the three valve intake ports 141, and the intake side 142 of the pump is connected to the three valve exhaust ports 143. Each valve 120, 121 is associated with two of the three downpass tubes 144 and serves to selectively connect the intake of pump 130 to one or the other of these two downpass tubes and to connect the

output of the pump to the other of said tubes 144. As indicated in Figure 1 each of these tubes 144 includes a flexible looped portion 144a, through which it is connected to a hydraulic cylinder 145, the three such cylinders being labelled 145a, 145b, and 145c, respectively, in Figure 2. These cylinders constitute operating units peculiar to each blade. Each such hydraulic cylinder 145 contains a piston 147 backed up by a spring 146 against which the hydraulic pressure must press. Integrally connected to each piston 147 is a piston rod 148 which has a right angle bend at its outer extremity, this bent portion passing through slot 149 in pitch control bell-crank 63. Each piston 147 constitutes a pitch adjusting unit of the previously mentioned secondary pitch adjusting means, for displacement of a piston 147 will rock the associated bell-crank 63 and through it raise or lower the corresponding pitch control rod 61 to adjust the pitch setting of the associated one of the blades 10. The pumping of fluid into a cylinder 145 forces its piston 147 and piston rod 148 outward, which through bell-crank 63 forces pitch control rod 61 upward which increases the pitch of the corresponding blade and causes the blade to rise due to aerodynamic forces. Therefore increase in the volume of fluid in a cylinder 145 raises the respective blade and conversely a decrease in such volume lowers the blade.

Slide valve 120a (Fig. 2) is positioned in response to differences in the effective flapping angle of blades 10a and 10b and in turn regulates the flow to and from the hydraulic cylinders 145a and 145b which adjust the pitch of these two blades, while slide-valve 120b is similarly positioned by differences between blades 10b and 10c and similarly adjusts the pitch of these two blades to eliminate such differences, and slide-valve 120c is similarly positioned by differences between blades 10c and 10a and adjusts the pitch of these two blades to eliminate such differences.

Operation of the blade tracking mechanism is as follows: For the purpose of illustration assume that blades 10b and 10c are tracking, but that blade 10a is travelling higher than the other two. This will cause the lever 97 which is associated with blade 10a to rotate slightly counterclockwise (as viewed in Fig. 1) about flapping hinge 17. This will cause vertical pin 106 on the corresponding slide 100 to move inward, carrying inward the lower end (as viewed in Fig. 2) of the lever 113 which is associated with slide-valve 120a. This will cause slide-valve 120a to move inward in valve-sleeve 121a. The inward movement of said vertical pin 106 will however also cause counterclockwise rocking of the bell-crank 107 with which it is associated, thus through link 109 causing outward movement of the right end (as viewed in Fig. 2) of the lever 113 associated with slide-valve 120c, thus causing said slide-valve to move outward in valve sleeve 121c. The inward movement of slide-valve 120a will cause hydraulic fluid to be pumped from the cylinder 145a, which is associated with blade 10a, and into the cylinder 145b, which is associated with blade 10b. This will lower the pitch on blade 10a and raise the pitch on blade 10b, thus causing decrease in the effective flapping angle of blade 10a and increase in that of blade 10b. The outward movement of slide-valve 120c will cause hydraulic fluid to be pumped from the cylinder 145a and into the cylinder 145c, which is associated with blade 10c. This will lower still further the pitch on blade 10a and raise the pitch on blade 10c thus further

lowering the path of blade 10a and raising that of blade 10c. Thus blade 10a will be lowered at twice the rate that blades 10b and 10c are raised. This process continues until all of the blades are tracking again, whereupon the centering of valves 120 terminates the process.

Thus if any blade stands at a flapping angle different from the mean of the flapping angles of all blades it will be caused to change its flapping angle in the direction of that mean at a rate substantially proportional to the amount of its departure from such mean value.

In view of the fact that the above described mechanism is operated in such a manner as to eliminate differences in effective flapping positions of the blades it would, if it operated rapidly enough, seriously interfere with the cyclic differences in flapping position, which constitute the accepted method of exercising control of the craft through an articulated rotor. To avoid this, either the openings 150 (Fig. 2) in all of the valves 120, or the fixed parts with which they cooperate, or both, are made of very slight dimension in the direction perpendicular to the plane of Figure 2 and they therefore serve to markedly throttle the rate of fluid flow, thereby serving as rate control means for the operating means. As shown in Figure 2 these openings 150 are of considerable width in the plane of Figure 2. By thus providing openings 150 which are of considerable width in the direction of travel of valves 120 (which is in the plane of Figure 2) and of very slight effective dimension in the direction perpendicular to the plane of Figure 2, the marked throttling effect provided by valves 120 is selectively altered by displacement of a valve 120 so that the flow through the valve opening is approximately proportional to the displacement of the valve from the position at which it completely cuts off the flow. This fact, combined with the fact that the valve displacement is arranged to normally be proportional to the difference in effective flapping angle, regulates the flow to an amount which is at least roughly proportional to such difference, thus providing for correction of the majority of each tracking error in approximately a constant period of time regardless of the amount of such error. With such an arrangement the functioning of this mechanism does not appreciably affect the amplitude of cyclic changes in blade position due to the fact that such changes normally involve equal amounts of movement of each blade above and below its mean flapping position and therefore in passing from its upper to its lower extreme position or vice versa it will be subject to two substantially equal and opposite increments of correction by the blade tracking mechanism, which increments will therefore substantially balance each other. The action of the blade tracking mechanism will have a tendency to advance all cyclic changes in blade path by a small and substantially constant and predictable azimuth angle, which therefore can be allowed for in orienting the cyclic control mechanism. It is therefore, practicable to construct the valves with openings sufficiently large to correct, for instance, approximately one-half of any given tracking error within a single cycle of rotor rotation.

By constructing valves 120 so as to provide a proportionately regulated throttling effect on the hydraulic flow the opposing requirements for promptly eliminating tracking errors and yet not disturbing cyclic blade differences are reconciled. Considerable latitude is possible in the degree of

such throttling that will give satisfactory results but there are rather sharply defined limits to such latitude. For instance if the throttling limits the flow to a rate proportional to the differences in effective blade positions, and if the vertical dimension of openings 150 is such that the flow during one cycle of normal rotor operation will eliminate half the difference in blade positions, then it will require 4.3 cycles to eliminate 95% of the error or about one and a fraction seconds, which is fully as short a time as will be required for introducing any marked change in flight conditions. Therefore, the response is rapid enough to provide substantially instantaneous correction of tracking errors.

The amount of correction that would be introduced in one quarter cycle is indicative of the amount of effect on cyclic control, and this should be a small fraction of the total error, not more than one-third in any case and preferably less. Any more rapid introduction of correction than this would commence to introduce secondary irregularities of objectionable size, due principally to the fact that the previously mentioned tendency of the blade tracking corrections to balance out in each half cycle of rotor operation is not perfectly attained if the amount of cyclic tilt of the rotor is not constant over the half cycle. For instance if the amount of cyclic tilt is 5% greater or less during the last half of such a half cycle period than it is during the first half of it, and if the correction effective in a quarter cycle is 0.33 of the difference existing then the secondary irregularity introduced would be

$$35 \quad 0.05 \times 0.33 = 0.0165$$

of the amount of cyclic difference in flapping position of two adjacent blades. This fact limits the rate at which correction should be introduced to not more than 0.80 of the tracking error in one cycle, for this rate corresponds to correction of 0.33 of the tracking error in a quarter cycle, which as above indicated is substantially the maximum that can be tolerated. At this rate 95% of the tracking error would be eliminated in 1.86 cycles, which is extremely prompt correction.

The lower limit on rate of correction is imposed by the fact that retracking should take place substantially as rapidly as flight conditions can change. On this basis not over 4 seconds should be allowed for 95% correction, which at 200 R. P. M. represents 13.3 cycles, which corresponds to 0.20 of the tracking error corrected in one cycle. At this rate only 0.054 of the error is corrected in one-quarter cycle, which would reduce the secondary irregularities above mentioned to one-sixth of the limiting values described.

Hence satisfactory operation will be secured if the rate of correction is held substantially within the range of 20% to 80% of the error corrected in one cycle of normal rotor operation, but departure much if any beyond this range commences to introduce either too slow a response or too marked irregularities upon rapid change of cyclic tilt.

As previously indicated the rate of correction may be established at any selected value by appropriately choosing the vertical dimension of valve openings 150. In order to secure the correction of a substantially constant fraction of any tracking error during each cycle it would be necessary for the remainder of the hydraulic system to be of sufficiently large cross-section to produce negligible friction loss. However, the permissible latitude in retracking rates is so

11

great that very considerable friction losses can be tolerated, so long as they are not so great as to cause the resultant retracking rate to fall substantially outside the limits hereinabove indicated as acceptable for blade differences within the range of such differences that may be due to tracking errors. For differences in blade positions greater than those which may be due to tracking errors, and such greater differences will ordinarily occur cyclically in connection with rotor tilt, it will not only be permissible for the tracking correction per cycle to become less than 0.20 of the difference, but highly desirable for it to do so for large cyclic differences. If the valve area is so related to the characteristics of the remainder of the hydraulic system that the amount of valve opening corresponding to the maximum difference in blade position caused by tracking errors permits almost as much hydraulic flow as the amount of flow that would pass through the system with the valve entirely removed, then the maximum rate of retracking for any amount of blade difference will be only slightly greater than that required for proper correction of maximum tracking errors. However, to provide greater latitude in the design of the system, and particularly in order to permit of faster correction of maximum tracking errors combined with sharper limitation on the maximum rate of retracking I prefer to provide the limit stops 122, previously described, arranged to limit the movement of valve 120 in each direction, and hence prevent any further increase in the rate of retracking, after the valve has been displaced from neutral by at least the distance corresponding to the maximum blade difference due to tracking error. In order that tracking errors combined with large cyclic blade differences may produce selective positioning of the valves adapted to reduce the tracking errors throughout a considerable part of the cycle, and in view of the fact that such selective positioning ceases while the valve is held against its limit stop, I prefer to place the limit stops so that they do not become effective until the valve has been displaced considerably beyond the position corresponding to the maximum tracking error itself, and to have the friction losses in the system such that they gradually reduce the percentage of error corrected per cycle for valve displacements intermediate between those corresponding to maximum tracking error and those at which the stops 122 are encountered.

With the blade tracking mechanism constructed in the particular manner which has been illustrated and above described, a difference in effective flapping angle of any two blades automatically initiates a readjustment of pitch on both of said blades in a manner tending to eliminate the difference. It is not essential, however, that pitch be readjusted on both blades for the difference could be eliminated by applying the correction to either of the two blades. For instance the valve 120c is positioned in accordance with the difference between the flapping angles of blades 10a and 10c. Through two openings in the valve sleeve 121c it is connected to tube 151 which connects it to the pitch adjusting mechanism of blade 10a, which is the leading one of these two blades, while through two other openings in the valve sleeve 121c it is connected to tube 152 which connects it to the pitch adjusting mechanism of blade 10c, which is the following one of these two blades. As previously described, if blade 10a is positioned at a higher flapping angle than blade 10c, hydraulic fluid

12

pumped through tube 151 operates to decrease the pitch on blade 10a, and that pumped through tube 152 operates to increase the pitch on blade 10c, until the difference in flapping angle is eliminated. However, if tube 151 and its openings through sleeve 121c were removed the difference would still be eliminated, for the fluid pumped through tube 152 would still operate to increase the pitch on blade 10c until the difference disappears. Thus if the three tubes which lead forward from the three valves and correspond to tube 151 were thus eliminated, or flow through them was permanently cut off, the blade tracking system would operate by bringing each 5 blade to automatically track the blade ahead 15 of it. If instead of eliminating the tubes corresponding to tube 151 the three corresponding to tube 152 were eliminated or plugged, the blade tracking system would operate by bringing each 20 blade to automatically track the blade next behind it. However, by including both sets of tubes appreciably prompter and more satisfactory tracking can be secured. For instance if as 25 previously assumed for illustration blades 10b and 10c are tracking but blade 10a is travelling higher, then with tubes 151 eliminated valve 120a acts to lower blade 10a to eliminate the difference 30 between blades 10a and 10b, while valve 120c acts to raise blade 10c to eliminate the difference 35 between blades 10a and 10c. Since there is initially no difference between blades 10b and 10c, valve 120b does not initially alter the pitch of blade 10b, but as blade 10c is raised a difference 40 between the positions of blades 10b and 10c develops and serves to raise blade 10b at a rate proportional to the amount it remains below blade 10c which would be at a slower rate than if it were also controlled by the difference between 45 blades 10a and 10b, as it will be in case all the 50 tubes illustrated in Figure 2 are functioning.

What I claim is:

1. In an aircraft having a sustaining rotor including a hub and a plurality of blades each attached to said hub by means permitting of 45 change in the angle subtended between the blade axis and the rotor axis and means permitting of change in the pitch angle, and primary pitch adjusting means connected to each of said blades; blade tracking means independent of said primary pitch adjusting means and comprising secondary pitch adjusting means, pitch controlling means for each of said blades comprising a member jointly positioned by said primary and said secondary pitch adjusting means, a member connecting each of said pitch controlling means to its respective blade so as to angularly position the blade in pitch, rate control means independent of said primary pitch adjusting means for controlling the rate of operation of said secondary pitch adjusting means, and including an adjustable element and connections from said blades to said adjustable element to position said adjustable element in accordance with differences in the angles subtended between the respective blades and the rotor axis.

2. The invention set forth in claim 1 in which the secondary pitch adjusting means comprises a plurality of pitch adjusting units each connected to a respective one of said blades to control the pitch angle thereof; said rate control means comprises a plurality of rate control units each including an element selectively positionable to control the rate of operation of one of said pitch adjusting units; and said connections 70 include a plurality of members each connected 75

13

to one of said elements and to a plurality of blades including the blade to which the respective pitch adjusting unit is related.

3. The invention set forth in claim 1, in which said blades are flexible, in combination with a member in conjunction with each blade, each of said members being mounted on the hub for movement relative thereto in response to vertical flexing of the blade, a part integrally attached to the blade in the outer half of the length thereof, and a flexible link connected to said part and to said member and extending inward along the blade and guided relative thereto so as to impart movement to said member upon vertical flexing of said blade, and in which said positioning of said adjustable element of said rate control means by said blades is effected through said members.

4. The invention set forth in claim 1, in which said means permitting of change in the angle subtended between the blade axis and the rotor axis comprises a flapping hinge and a flexible root portion of said blade, in combination with a member in conjunction with each blade, each of said members being mounted on the hub for movement relative thereto in joint response to the flexing of the blade and the displacement of the blade upon its hinge relative to the hub, a part integrally attached to the blade in the outer half thereof and a flexible link connected to said part and to said member and extending inward along the blade and guided relative thereto so as to impart movement to said member upon vertical flexing and/or displacement of said blade relative to said hub, a connection from said flexible link to said member along a line removed from the axis of said flapping hinge, and in which said positioning of said adjustable element of said rate control means by said blades is effected through said members.

5. In an aircraft having a sustaining rotor including a hub and a plurality of blades each attached to said hub by means permitting of change in the flapping angle and by means permitting of change in the pitch angle of the blade; pitch adjusting means for each of said blades comprising a cyclic pitch control member, manually positionable means mechanically controlling the position of said member, a pitch adjusting member, means for automatically positioning said member under joint control of two of said blades in accordance with the respective flapping angles of said two blades, a pitch setting member connected to said blade at a point remote from the blade axis so as to determine the angular position of said blade about said axis, and positioning means for said pitch setting member jointly positioned by said cyclic pitch control member and said pitch adjusting member and consisting of mechanical linkage extending from said cyclic pitch control member and said pitch adjusting member to said pitch setting member.

6. The invention set forth in claim 5 wherein the means for automatically positioning the pitch adjusting member comprises rate control means selectively settable to correspondingly determine the rate of such positioning, an element, connections from said element to each of two of said blades to position said element in accordance with the difference between the effective flapping angles of said two blades, and means connecting said element to said rate control means to set said rate control means in accordance with the position of said element.

7. The invention set forth in claim 6 in com-

14

bination with a surface connected to said rate control means and a cooperating surface fixed in the path of movement of said first mentioned surface, so as to block said surface and thereby limit the range of positions to which said rate control means may be set by said element.

8. In an aircraft having a sustaining rotor including a hub and a plurality of flexible blades attached to said hub by means including a pitch changing hinge constituting a pivotal support having an axis longitudinal of the blade; blade tracking means including a pitch adjusting member connected to one of said blades at a point remote from said pitch changing hinge so as to selectively alter the pitch thereof in accordance with the displacement of said pitch adjusting member, means for automatically displacing said pitch adjusting member under joint control of two of said blades in accordance with the difference in the vertical flexural position of said two blades including two parts each associated with a respective one of said two blades and integrally attached to the blade in the outer half of the length thereof, two flexible links each associated with a respective one of said two blades and connected to the respective one of said two parts and extending inward along the blade and guided relative thereto along a path vertically displaced from the neutral axis of the blade, a lever connected to each of said two links and jointly positioned by them, operating means for applying power from said source to said pitch adjusting member to displace same, adjusting means for selectively adjusting said operating means to control the direction and rate at which said power is supplied, and a connection from said lever to said adjusting means to adjust said operating means in joint response to the flexing of said two blades.

9. In an aircraft having a sustaining rotor including a hub and a plurality of flexible blades each attached to said hub by means comprising a flapping hinge and a pivotal mounting substantially parallel to the axis of the blade; blade tracking means including a pitch adjusting member connected to one of said blades at a point remote from said pivotal mounting so as to angularly displace said blade on its respective pivotal mounting in accordance with the displacement of said pitch adjusting member, means for automatically displacing said pitch adjusting member under joint control of two of said blades in accordance with the difference in their effective vertical positions as determined by their respective angular displacements about their respective flapping hinges plus their respective vertical flexural displacement, including two parts each associated with a respective one of said two blades and integrally attached to the blade in the outer half of the length thereof, two flexible links each attached to a respective one of said parts and extending inward along the blade and guided relative thereto along a path vertically displaced from the neutral axis of the blade, a lever, a connection from each of said links to said lever, each of said connections being vertically displaced from the respective flapping hinges, a source of power, operating means for applying power from said source to said pitch adjusting member to displace same, adjusting means for selectively adjusting said operating means to control the direction and rate at which said power is supplied, and a connection from said lever to said adjusting means to adjust said operating means in joint response to the flexing of said two blades.

15

10. In an aircraft having a sustaining rotor including a hub and a plurality of blades each attached to said hub by means permitting of change in the flapping angle of the blade and means permitting of change in the pitch angle of the blade; blade tracking means comprising a hydraulic pump, a hydraulic cylinder having a piston, a hydraulic connection from the pump to the cylinder to operate the piston, a valve interposed in said connection between said pump and said cylinder for controlling the operation of said piston by said pump, linkage connecting said valve to two of said blades to position said valve in accordance with the difference of the flapping angles of said two blades, a manually positionable pitch controlling element, a pitch controlling member connected to said element and said piston so as to be jointly positioned by said element and by said piston, and mechanical linkage connecting said pitch controlling member to one of said two blades to establish the pitch angle thereof.

11. The invention set forth in claim 10 in which said valve is provided with ports which are of slight dimension in the direction perpendicular to the travel of the valve and to the direction of flow of the fluid through the valve as compared to their dimension in the direction of travel of the valve.

12. In an aircraft having a sustaining rotor including a hub and a plurality of blades each attached to said hub by means permitting of change in the flapping angle of the blade and a pivotal mounting substantially parallel to the axis of the blade; blade tracking means including a plurality of pitch adjusting members each connected to a respective one of said blades so as to angularly position said blade on its respective pivotal mounting, a plurality of controlling members mounted on the hub for individual displacement relative thereto, linkage connecting each of said blades to two adjacent ones of said controlling members and thereby connecting each controlling member to two adjacent blades to automatically displace said controlling member relative to said hub in accordance with the difference between the flapping angles of said two blades, an operating connection to each pitch adjusting member from the two controlling members which are connected to the blade to which said pitch adjusting member is connected for displacing said pitch adjusting member.

13. In an aircraft having a frame and a sustaining rotor including a hub rotatable with respect to said frame and a plurality of blades each attached to said hub by means permitting changes in the flapping angle and pitch thereof; pitch changing mechanisms comprising a pitch control spider tiltably supported with respect to its center, a plurality of bell-crank levers, a fulcrum on said spider for each of said bell-crank levers, each fulcrum mounting its respective lever for rocking movement in a vertical plane and means connecting an arm of each of said levers with one of said blades for changing the pitch of said connected blade upon displacement of said fulcrum in a vertical plane or upon rocking of said spider upon its fulcrum; separate primary and secondary adjusting means connected with said pitch changing mechanism, said primary adjusting means comprising a train of mechanism

16

carried by said frame and connected to said spider to tilt same; and said secondary adjusting means comprising a plurality of hydraulic cylinders mounted on said spider, a piston in each of said cylinders connected with a second arm of a respective one of said bell-crank levers; and a control system for said secondary adjusting means comprising a source of fluid pressure, a connection between each of said cylinders and said source, valve means including an adjustable element interposed in each of said connections, a lever fulcrumed on each of said adjustable elements, means including a connection between one of said blades and a point on one of said levers spaced from the fulcrum thereof for adjusting said element in one direction upon upward flapping movement of one of said blades, and means including a connection between another of said blades and a point on one of said levers oppositely spaced from the fulcrum thereof for adjusting said element in the opposite direction upon upward flapping movement of said other of said blades.

14. The invention set forth in claim 13 in which said valve means includes a throttling passage partially opened in selective amounts by the displacement of said adjustable element whereby the amount of fluid supplied to said cylinders by said source of fluid pressure is proportioned to the difference between the flapping angles of the blades connected to said element.

15. In an aircraft having a frame and a sustaining rotor including a hub rotatable with respect to said frame and a plurality of blades each attached to said hub by means permitting changes in the flapping angle and pitch thereof; pitch changing mechanisms comprising a pitch control spider, a plurality of devices mounted on said spider and movable either by said spider or relatively thereto in a substantially vertical direction, and means connecting each of said devices with one of said blades for changing the pitch of the connected blade upon either such movement of said device; separate primary and secondary adjusting means connected with said pitch changing mechanisms, said primary adjusting means comprising manually operable means for moving said spider and the said devices mounted thereon in a substantially vertical direction, and said secondary adjusting means comprising means carried by said hub and responsive to said blades upon changes in the flapping angles thereof for moving said devices relatively to said spider in a substantially vertical direction.

HAROLD T. AVERY.
